UNITED STATES PATENT OFFICE.

MURDOCK WILLIAM MELROSE, OF NORTH BELLINGHAM, MASSACHUSETTS.

VALVE-SPRING LIFTER.

1,299,496.

Specification of Letters Patent. Patented Apr. 8, 1919.

Application filed March 18, 1918. Serial No. 223,095.

To all whom it may concern:

Be it known that I, MURDOCK WILLIAM MELROSE, a citizen of the United States, residing at North Bellingham, in the county of Norfolk and State of Massachusetts, have invented new and useful Improvements in Valve-Spring Lifters, of which the following is a specification.

This invention relates to tools for removing from the stem of an internal combustion engine valve, the stress of the spring which yieldingly holds said valve to its seat, and thereby permit the removal of the valve when it becomes necessary to grind or clean the same.

The invention is embodied in the improvements hereinafter described and claimed in a lifter constituting a jack adapted to act in lifting the spring and removing its stress from the valve stem.

Of the accompanying drawings forming a part of this specification,—

Figure 1 is a top plan view of a spring lifter embodying the invention.

Fig. 2 is a side view of the same, and a side view of a portion of the engine.

Fig. 3 is a vertical section of the spring lifter, and a sectional view of the portion of the engine shown by Fig. 2.

Fig. 4 is an end view of the lifter.

Fig. 5 is a section on line 5—5 of Figs. 2 and 4.

Fig. 6 is a fragmentary view, showing in section one of the standards of the base hereinafter described, and in elevation a portion of the lever, said parts being separated.

Fig. 7 is a view similar to Fig. 1, illustrating means for varying the width of the lifter.

Fig. 8 is an end view of the lifter shown by Fig. 7.

Fig. 9 is a section on line 9—9 of Fig. 7.

Figs. 10 to 13, inclusive, represent a modified construction providing means for vertically adjusting the fulcrum members hereinafter described, Fig. 10 being a top plan view, Fig. 11 an end view, Fig. 12 a section on line 12—12 of Fig. 10, and Fig. 13 a section on line 13—13 of Fig. 11.

Fig. 14 is a perspective view, representing a non-adjustable embodiment of the invention.

Fig. 15 is a side view of the embodiment shown by Fig. 14, in position to hold the valve spring lifted.

Fig. 16 is a perspective view of the lever, illustrating a modified construction thereof.

The same reference characters indicate the same parts in all of the figures.

I will first describe the construction shown 60 by Figs. 14 and 15.

The elements of the spring-lifting jack shown by said figures are a thrust member adapted to bear on a fixed support adjacent to a valve spring 12, shown by Figs. 2 and 3, 65 the support being portions of the casing 13 of the engine, at opposite sides of a guide 14 thereon, a lever fulcrumed on said thrust member and having longer and shorter arms, the shorter arm being composed of 70 two spaced apart members, and a stirrup pivotally connected to the shorter arm members of the lever, and formed as an abutment, adapted to bear on the usual spring-supporting washer 17, which is in turn supported by a cotter-pin 18, removably inserted in the stem 19 of the valve 20.

The thrust member includes two spaced apart standards 21, connected by a transverse tie-rod 22, and provided with feet 23 80 adapted to bear on said support.

The longer arm of the lever as here shown, includes two spaced apart members 24, connected at their outer ends by a neck 25 and two spaced apart shorter arm members 26. 85 I desire it understood, however, that the longer arm may be composed of a single member 27, as shown by Fig. 16. The lever is connected with the standards 21 by fulcrum studs 28 between the longer and 90 shorter arms.

The stirrup member includes a recessed abutment 29, adapted to impart pressure from the lever to the valve spring, through the washer 17, and a pair of spaced apart 95 upstanding ears 30, projecting from opposite ends of the abutment 29 and connected by pivot members 31 with the shorter arm members 26.

The stirrup depends from the shorter arm members and is adapted to swing between the same. It is preferably provided with a positioning stop 32 at its central portion, adapted to bear against one or more of the lower convolutions of the spring 12, as indicated by Fig. 3, thus positioning the stirrup relatively to the spring and washer.

The standards 21 and feet 23 may be made from two strips of metal twisted below the tie-rod 22, as indicated by Fig. 14, and 110

curved so that their lower ends, which form narrow bearings adapted to rock on the support 13, are offset inwardly from the standards 21. The object of this arrangement is to enable the feet to bear on the support 23 at two points in substantially the same vertical plane as the pivot members 31, the feet 23 and the rod 22 constituting a fork adapted to best ride or receive the base 10 of the guide 14.

The abutment portion 29 of the stirrup may be placed under the washer 17, the feet 23 being at the same time placed on the support 13. If, now, the longer arm of the 15 lever is swung downwardly, the stirrup is raised, and raises the washer 17 from the cotter-pin 18, and at the same time, compresses the spring 12. The shorter arm members 26 are arranged at an angle to the 20 longer arm, the arrangement being such that when the longer arm is depressed, as shown by Fig. 15, and the maximum compression of the spring is attained, the fulcrum members 28 are at one side of a 25 straight imaginary line extending between the extremities of the feet 23 and the pivots 31, so that the jack is adapted to support the spring in a raised or compressed position, independently of the operator, who 30 may leave the lifter or jack in the position shown by Fig. 15, while removing the cotter-pin and withdrawing the valve from the engine. Owing to the fact that the feet 21 are adapted to bear on opposite sides of the 35 guide 14, said guide constitutes a stop preventing the jack from slipping sidewise or in a direction at right angles to the plane in which the lever swings.

The foregoing description is applicable to 40 each of the figures of the drawing, Figs. 1 to 13, inclusive, showing certain structural features, providing for various adjustments of the device, as will be next described.

As shown by Figs. 1 to 6, inclusive, the 45 standard portions of the thrust member are each composed of a lower member 21^a and an upper member 21^b, said members being telescopic and constituting a vertical adjustable standard, the members of which 50 may be connected to maintain different heights of the standard by transverse pins 33 inserted in orifices in the members, there being a plurality of orifices. Each member 21^b is provided with a plurality of open 55 bearings 34, adapted to receive the fulcrum members 28, said members being preferably trunnions attached to the lever members. The fulcrum members, therefore, may be located at different heights on the standards. The tie-rod 22^a connecting the standards is shown as curved between the standards, to prevent liability of its contacting 60 with the guide 14.

The longer arm members may be adjustable in length, as shown by Figs. 1 and 2,

the members 24 being supplemented by members 24^a adapted to slide on the members 24, and connected by a neck 25^a.

As shown by Figs. 10 to 13, inclusive, the base standards are screw-threaded rods 21^c, 70 on which collars 37 are adapted to slide vertically, said collars being supported by nuts 38 engaged with the threaded standards. Each collar 37 has a sleeve 39, said sleeves carrying the fulcrum members 28. By adjusting the nuts 38, the fulcrum members may be raised and lowered to vary their height. 75

As shown by Figs. 7, 8, and 9, provision is 80 made for varying the width of the lifter or jack. The stirrup member is composed of two slidably or telescopically connected parts 29^a, one having a socket 40, and the other a tongue 41 slidable in said socket. The standards which may be constructed as 85 shown by Figs. 1 to 6, are connected by a telescopic tie-rod composed of bent members 42, one having a right hand, and the other a left hand screw thread, and a turn buckle 43 engaged with said threads. The longer 90 lever arm members 24 are connected by a transverse neck, composed of two members 44, one having a right, and the other a left hand screw-thread, and a turn buckle 45 engaged with said threads. 95

Provision is made in each embodiment of the invention for minimizing the liability of slippage of the base feet on the standard 13. To this end, the feet may be provided with downwardly facing teeth or corrugations 47, as shown by Figs. 14 and 15, or with downwardly projecting pins or studs 48, as shown by Figs. 2 and 4, and by other figures. The lower ends of said studs may be concaved or cut to form relatively sharp 105 edges that engage the support 13.

Either form of the device shown and described is adapted to be folded in a relatively small compass for storage and shipment. 110

The spaced apart offset feet 23 bearing on the support 13 at opposite sides of the guide 14, enable the operator to correctly position the jack with reference to the spring, the feet being directed by the guide 115 when the operator is installing the jack in its operative position.

I claim:

1. A valve spring lifting jack which comprises a lever having longer and shorter 120 arms, the shorter arm including two spaced apart members, a valve-spring-engaging stirrup pivoted to the outer ends of the shorter arm members, fulcrum studs connected with said lever between the shorter 125 and longer arms thereof, and a thrust member having bearings supporting said fulcrum studs, said jack being characterized by the fact that the thrust member is composed of two parallel standards carrying said bear- 130

- ings, transverse connecting means rigidly connecting said standards and maintaining the same in spaced relation, and offset spaced apart feet rigidly connected with the lower 5 ends of the standards and adapted to bear on a support at opposite sides of a fixed guide in alinement with a valve stem, and engage said guide to position the jack and prevent it from slipping sidewise.
- 10 2. A valve spring lifting jack which comprises a lever having longer and shorter arms, the shorter arm including two spaced apart members, a valve-spring-engaging stirrup pivoted to the other ends of the 15 shorter arm members, fulcrum studs connected with said lever between the shorter and longer arms thereof, and a thrust member having bearings supporting said fulcrum studs, said jack being characterized by 20 the fact that the thrust member is composed of two parallel standards carrying said bearings, transverse connecting means rigidly connecting said standards and maintaining the same in spaced relation, and offset spaced 25 apart feet rigidly connected with the lower ends of the standards and adapted to bear on a support at opposite sides of a fixed guide in alinement with a valve stem, and engage said guide to position the jack and prevent 30 it from slipping sidewise, the said standards being provided with means for sup-
- porting the spaced apart fulcrum studs at different distances from the spaced apart feet to enable the jack to coöperate with valve springs of different lengths. 35
3. A valve spring lifting jack which comprises a lever having longer and shorter arms, the shorter arm including two spaced apart members, a valve-spring-engaging stirrup pivoted to the outer ends of the 40 shorter arm members, fulcrum studs connected with said lever between the shorter and longer arms thereof, and a thrust member having bearings supporting said fulcrum studs, said jack being characterized by 45 the fact that the thrust member is composed of two parallel standards carrying said bearings, transverse connecting means rigidly connecting said standards and maintaining the same in spaced relation, and offset 50 spaced apart feet rigidly connected with the lower ends of the standards and adapted to bear on a support at opposite sides of a fixed guide in alinement with a valve stem, and engage said guide to position the jack and 55 prevent it from slipping sidewise, the said transverse connecting means being adjustable to permit a variable spacing of the standards.

In testimony whereof I have affixed my 60 signature.

MURDOCK WILLIAM MELROSE.
